STUDY CARREL

Frank R. Torrey, 9805 Dallas Ave.,
Silver Spring, Md. 20901

Filed Feb. 19, 1971, Ser. No. 117,195

Term of patent 14 years

Int. Cl. D6—04

U.S. Cl. D6—181

FIG. 1

FIG. 2

FIG. 3

FIG. 1 is a perspective view of a study carrel, showing my new design;

FIG. 2 is a rear elevational view thereof, and

FIG. 3 is a right side elevational view, the left side being a mirror image thereof.

I claim:

The ornamental design for a study carrel, as shown and described.
